AUTOMATIC NEEDLE STOP FOR BRISTLING
MACHINEWilliam Penn-Gaskill Hall, Berwyn, Pa., assignor
to E. I. du Pont de Nemours & Company, Wil-
mington, Del., a corporation of Delaware

Application June 27, 1940, Serial No. 342,767

14 Claims. (Cl. 300—8)

This invention relates in general to bristling machines in the brush making art, and more particularly to an automatic stop mechanism for a brush tuft setting mechanism.

Objects of the invention include the provision of a new and improved brush tuft-setting needle mechanism having automatic means for the immediate stopping of the power therefor upon the engagement of the needle with any obstruction or hard object which it is not intended that the needle shall penetrate; the provision of an automatic needle stop mechanism in which the needle is driven through the medium of resilient means of such tension that the needle will be rigidly driven into the holes into which the tuft of bristles is to be inserted, but which will yield upon the engagement of the needle with any defective brush blank which has been improperly drilled or which lacks any of the requisite holes, to operate a switch to shut off the power; the provision of an automatic needle stop mechanism in which the needle is driven thru a compressed spring which will yield to allow the needle to retreat to operate a switch and shut off the power when the needle encounters an obstruction, and in which the spring tension may be adjusted; and the provision of an automatic needle stop for brush tuft-setting machines, in which a micro-switch is used as the power interrupter, and which is provided with a device for the adjustment of the point of operation of the same.

Other objects and advantages of the invention will appear hereinafter.

Reference is to be had to the accompanying drawing, in which

Fig. 1 is a sectional view thru the entire needle mechanism forming the present invention and showing the parts in operative position;

Fig. 2 is a sectional view of the top part of the mechanism showing the parts in power stopping position;

Fig. 3 is a view in elevation of the switch supporting bracket;

Fig. 4 is a plan view of Fig. 3, looking in the direction of the arrow 4;

Fig. 5 is a view in elevation of a nut for the spring adjustment;

Fig. 6 is an elevation of the top part of the needle tube or cylinder;

Fig. 7 is an elevation of the lower end of the needle chuck; and

Fig. 8 is an enlarged section on line 8—8 of Fig. 1.

As shown in Fig. 1, a brush 10 is to have its

bristle tufts 12 inserted by means of a needle 14, which is vertically reciprocated by means of tube or cylinder 16 in guide 18. The tube 16 is reciprocated by a convenient crank or lever pivotally attached thereto, not here shown but which may be similar to levers 182 or 233 in Patent No. 1,846,141 to Person. It is to be understood that a tuft of bristles is fed to the needle as by a bristle picker, and the needle 14 descends, engages the center of the tuft, doubles the same in a convenient die, and continuing to descend, inserts the doubled tuft in the brush 10 in conjunction with an anchor, as in the above mentioned patent. As the needle ascends, a further tuft is brought into place, and the operation is repeated. It sometimes happens that the brush is improperly placed or drilled, or is not provided with the requisite holes, or an obstruction gets in the way of the needle, and the needle then breaks unless the power to the device can be simultaneously shut off. To this end the present invention is directed, and it provides means to shut off the power immediately upon the engagement of the needle with an undesired obstacle or obstruction.

A needle chuck 20 is provided, this chuck being keyed at 22 for longitudinal but non-rotational movement in the tube 16. The flat bladed needle 14 is held in the lower end of the chuck by means of a semi-circular backing up element 24 and set screws 26. The upper end of the chuck has a tapped hole 28 for the threaded reception of a long needle rod 30 having a lock nut 32 for the accurate positioning of the rod in the chuck. Towards the upper end of the rod, it is enlarged in diameter and threaded as at 34 for a purpose to be explained, and the rod will be seen to extend thru the tube 16 and on out thru the top thereof.

A ferrule 36 having a relatively long hollow screw threaded portion 38 is adapted to be slid into the needle tube 16, but is not threaded therewith. Instead, an enlarged threaded head 40 is provided at the top of the tube, and a screw cap 42 threaded on the ferrule engages with this head. A lock nut 44 holds the cap in place. It will be seen that needle rod 30 extends all the way thru this ferrule and projects outwardly from the top thereof, and that the ferrule, ending at the washer 46, provides a rigid abutment for a compression spring 48 at one end thereof, the lock nut 32 forming the other abutment, the latter being adjustable to vary the tension of spring 48.

Spring 48 is relatively heavy and is adapted to be somewhat compressed so that motion of tube 16 in a vertical direction is transmitted thru head 40, screw cap 42, ferrule 36, and spring 48, to the chuck 20, so that needle 14 is reciprocated to set the bristle tufts without any normal resilient action. However, spring 48 is heavy enough so that it need not be fully compressed to obtain the above stated action and is therefore yieldable even under these circumstances, when the needle strikes a hard object, i. e., the undrilled or imperfect brush blank or other obstruction; thus it is not necessary to completely close the coils of the spring in order to make the needle enter the brush blank holes to set the tufts on the down stroke of tube 16. The compression of spring 48 may be varied by turning nut 50 on the screw 34, or by adjusting lock nut 32 and then backing it by turning upon the chuck 20.

The upper end of the ferrule is enlarged as shown and is provided with a hollow chamber for the reception of a cylindrical nut 50 which is threaded onto the enlarged end 34 of the needle rod. A pair of diametrically opposed arms 52 rise from the enlarged end of the ferrule and support an end ring or closed track 54 while allowing convenient access to nut 50. The upper end of needle rod 30 projects thru the nut 50, and is adapted to support a microswitch 56 by means of a yoke 58 having a head 60 which is screw threaded to receive the end of the needle rod, and to form a lock nut for the element 50. The nut 50 holds the head 60 and switch 56 in desired position.

A plunger 62 is mounted to slide in a tube 64 on the switch, and this plunger is spring pressed outwardly. The plunger controls the switch and is so arranged that when extended by its spring, the switch is open, and when pressed slightly into its tube, the switch is closed. This type of switch is well known and it is not thought necessary to disclose it in detail. Adjustment of the point of operation of the switch 56 may be accomplished by adjusting the switch relative to its yoke 58 by means of slots 59 in the yoke, through which screws 59' extend to connect the switch to the yoke.

The entire mechanism shown in Fig. 1 normally reciprocates vertically when the needle tube 16 is reciprocated, since although the needle rod is not directly connected to the ferrule, still the tube moves the spring 48 as though it were a rigid link, thru the intermediary of the ferrule, and this in turn moves chuck 20 and needle rod 30. Therefore, the parts of the mechanism will always be in the relation shown in Fig. 1, even though the needle tube is operating, until the needle strikes a hard object or a defective blank. When this happens, the spring 48 yields slightly under pressure of the needle, and the latter thus raises the needle rod relative to the needle tube and ferrule. Head 60 is thereby moved slightly upwards, thus allowing plunger 62 to extend and move off ring 54, shutting off the power. This disposition is illustrated in Fig. 2, wherein the plunger is shown free of the ferrule ring, and the rod 30 is in its raised position relative to the ferrule. Upon removal of the obstruction or defective blank, the spring 48 returns the needle 70 to operating condition and the switch to closed condition, so that the bristling machine may again be operated with little loss of time. Also, the needle is not in danger of being broken due to repeated engagement with the obstruction, and 75

thus faster and more economical operation of the machine results, due to the provision of the present novel construction.

Having thus described my invention and the advantages thereof, I do not wish to be limited to the details herein disclosed, otherwise than as set forth in the claims, but what I claim is:

1. In a bristling machine, a support adapted to be reciprocated, a needle rod slidably mounted with relation to said support and mounting a needle at one end and a switch at the other end, means normally retaining said support and said rod in fixed relation, and means on the support effective to operate said switch upon relative movement of said rod and said support.
2. In a bristling machine, a reciprocable support, a needle rod slidably mounted with relation to said support, a switch mounted on said rod and having an operating means associated with said support, whereby relative movement of said rod and support will operate said switch, and means normally preventing such relative movement.
3. In a bristling machine, a needle chuck, a ferrule spaced therefrom, a resilient member at least partially compressed between said chuck and said ferrule, a switch, means rigidly connecting said switch and said chuck, and switch operating means on said ferrule, the latter and said chuck being capable of relative movement.
4. In a bristling machine, a needle tube, a needle chuck located in said tube, a ferrule in said tube, a spring in said tube compressed between said needle chuck and said ferrule, said ferrule and chuck being capable of relative movement, means extending from said chuck and mounting a switch, and a switch actuating member on said ferrule.
5. In a bristling machine, a movable needle tube, a needle chuck in said tube, a ferrule connected to said tube and spaced from said chuck, a spring partially compressed between said chuck and ferrule whereby chuck and ferrule normally move with the tube, a switch, means mounted on said chuck and supporting said switch, and means on said ferrule to operate said switch upon further compression of said spring and consequent movement of said chuck relative to the ferrule.
6. In a bristling machine, a needle tube, a rod in said tube mounting a needle and a switch, means associated with said tube to operate said switch upon relative movement of said rod and said tube, means normally preventing such movement and thereby acting as a rod driving link, said last mentioned means being constructed and arranged to yield upon engagement of said needle with an obstruction, whereby said needle and rod will move with respect to said tube to thereby operate said switch.
7. In a bristling machine, a reciprocable needle tube, a needle rod normally movable with said tube, a switch connected with said needle rod, means associated with said tube for operation of said switch upon relative movement of said rod and tube, means mounting said rod and said tube for relative movement comprising a relatively stiff spring member constructed and arranged to be non-yieldable under normal conditions of operation so as to act as a rod driving means.
8. In a bristling machine, a needle tube, a needle rod slidably mounted in said tube and mounting a needle at one end and a switch at the other end, means associated with said tube adjacent the switch to operate the latter upon

relative movement of said rod and said tube, means normally causing said rod and tube to be movable together to set bristles in a blank, and constructed and arranged to yield to permit relative movement of the parts under certain conditions of operation.

9. In a bristling machine, a needle tube mounted for reciprocation, a needle chuck mounted in said tube and holding a needle, a needle rod secured to said chuck, a ferrule secured to said tube, said rod extending thru said ferrule, a spring in said tube and bearing against said ferrule at one end and said chuck at the other end, said rod mounting a switch at its extending end, and means on said ferrule adapted to engage a switch actuator on said switch, said spring being adapted to drive said rod.

10. In a bristling machine, a needle, a needle supporting member, and a longitudinally spaced ferrule member, a spring between said members, said spring being compressed to such a degree that it acts as a rigid element when said ferrule member is reciprocated to set bristles in prepared holes in a brush blank, said spring being set to be yieldable upon the engagement of said needle with an obstruction so that said needle and its supporting member may retreat relative to said ferrule member, a power interrupter on one of said members, and means mounted on the other member and constructed and arranged to operate said interrupter upon the retreat of said needle.

11. In a bristling machine, a needle tube, a needle in said tube, a ferrule adjustably mounted on said tube and having an extension there-within, a spring compressed between said needle and ferrule extension, a rod connected with said needle, a switch on said rod, and means on said ferrule to operate said switch upon further compression of said spring.

12. In a bristling machine, a needle for setting tufts of bristles, a rod connected with said

needle, a switch mounted adjacent an end of said rod and adjustable with respect thereto, a ferrule thru which said rod extends, means on said ferrule to operate said switch upon relative movement of said rod and ferrule, and compression spring means normally preventing such movement.

13. In a stop motion for a bristling machine or the like, a supporting member, a needle holding member associated with said supporting member, a needle adapted to be secured to said needle holding member, means to reciprocate said members together, said means including a resilient element located between said members and under sufficient tension to drive said needle into the holes of a blank to be bristled, said resilient element being yieldable to allow said needle member to retreat relative to said supporting member upon engagement of said needle with an obstruction, a power interrupter for said reciprocating means, said interrupter being mounted on one of said members, and means mounted on the other of said members for operating said interrupter upon such retreat.

14. In a stop motion for a bristling machine or the like, the combination of a movable supporting member, means to move said member, a needle, a needle holding member connected to said supporting member, and a resilient element located between said members and effective to normally rigidly secure the same, said element being yieldable to permit relative movement of said members upon engagement of said needle with an obstruction; with a power interrupting device mounted on one of said members, and means associated with the other member to operate said device upon said relative movement, said device being located in the path of movement of said last named means relative to said one member.

WILLIAM PENN-GASKILL HALL.
